UNITED STATES PATENT OFFICE.

GEORGE W. UTSMAN, OF DURHAM, NORTH CAROLINA, ASSIGNOR TO WILLIAM D. HESTER, OF DURHAM, NORTH CAROLINA.

QUILL-CLEANING MACHINE.

1,235,399.

Specification of Letters Patent. Patented July 31, 1917.

Application filed September 29, 1914. Serial No. 864,075.

To all whom it may concern:

Be it known that I, GEORGE W. UTSMAN, a citizen of the United States, residing at Durham, in the county of Durham and State 5 of North Carolina, have invented certain new useful Improvements in Quill-Cleaning Machines; and I hereby declare that the following is a full, clear, and exact description thereof, reference being had to the accompanying drawings, which form part of this 10 specification.

This invention is a novel machine for stripping or cleaning bobbins or "quills" commonly used in connection with cotton 15 weaving machinery. The cotton or thread is wound upon these quills and when the thread is unwound therefrom usually various strands or pieces of thread adhere to the quill and must be removed before a fresh 20 supply of thread is wound upon the quill. The bobbins or quills have been usually cleaned by hand, and such operation is troublesome and slow. The object of the 25 present invention is to provide automatically operating machinery for cleaning such bobbins or quills, and the invention includes novel mechanism for cleaning the quills successively as hereinafter explained.

The invention is capable of embodiment in 30 various forms when once understood, and I will explain same in connection with an operative form of apparatus illustrated in the accompanying drawings, in which—

Figure 1 is a side elevation of the complete 35 bobbins or quill stripping machine.

Fig. 2 is a top plan view thereof showing it in quill releasing position.

Fig. 3 is a top plan view showing it in quill stripping position.

Fig. 4 is a detail vertical section on line 4—4, Fig. 1.

Fig. 5 is a detail section on line 5—5, Fig. 3.

The machine shown in the drawings is 45 composed of a plurality of side bars 1 and end and intermediate bars 1^a mounted upon standards 1^c. Upon one end of this frame is mounted a hopper 9 in which the quills or spindles 10 are placed and which has 50 an opening in its lower end through which the quills successively drop into position to be engaged by the quill stripping and gripping devices. The quill strippers are shown as metal plates 6^b attached to the free ends 55 of opposite levers 6 which are pivoted at 6^a

upon an intermediate transverse bar 1^a of the frame in rear of the hopper. These levers 6 are normally swung inward so as to cause the plates 6^b to engage a quill 10 by means of springs which are arranged in 60 any suitable manner, but are shown as helical springs 8 attached at 6^a to lever 6 and at 1^a to the side bars of the frame. The strippers 6^b have notches 6^c in their opposed faces to enable them to properly engage the 65 surface of the bobbin or quill to be cleaned.

A reciprocating cross head 3 is shown as slidably mounted upon guide bars or rods 5, the forward ends of which are pivoted at 5^a to the levers 6, and their rear ends are 70 mounted on brackets 7 on the side bars 1.

The cross head 3 may be reciprocated in any suitable manner, and is shown as pivotally connected at 3^a to one end of a pitman 2^b, the other end of which is connected 75 to a crank 2^a on a transverse shaft 2 journaled in bearings 2^c on side bars 1, and shaft 2 may be driven by any suitable means, as by a belt 2^d engaging a pulley 2^e on said shaft, and actuated from any suitable motor 80 or driver not shown. As the shaft rotates the cross head 3 is reciprocated back and forth upon the guides 5.

To the cross head 3 are connected the rear ends of horizontally disposed grippers 4, 85 the forward ends of which are shown as provided with inwardly projecting teeth 4^a adapted to engage the head of a bobbin or quill 10 lying in the bottom of hopper 9. The toothed ends of the grippers may be drawn toward each other by means of a spring 4^b, connected to said grippers in any suitable manner. The grippers may be opened to engage a bobbin at the proper time by any suitable means. As shown, to one 90 of these grippers 4 is connected a spreader 4^c, which may be pivoted thereto as at 4^d, if desired, and the free end of this spreader projects through a slot 4^e in the opposed gripper 4 into position to engage with stops 1^b and 1^c, the former of which is attached 95 to the cross piece 1^a adjacent the hopper, and the other to the intermediate cross piece 1^a to which the levers 6 are pivoted.

The guides 5 are shown as provided with 105 adjustable stop nuts 5^c with which the cross-head engages when it is drawn back to rear-most position, see Fig. 2, and thus causes the guides 5 to swing levers 6 so as to separate the strippers 6^b. The closing move- 110

ment of the strippers may be regulated by nuts 5^b on the rear ends of the guides 5.

As the cross-head 3 reaches its rearmost position, Fig. 2, the free end of spreader 4^c engages stop 1^e and is swung thereby into the position indicated in Fig. 2, spreading the grippers 4 apart and releasing the bobbin, and the spreader 4^c will hold the grippers open until the cross head moves inward 10 and the gripper ends are in position to engage the head of a spindle 10 in the bottom of the hopper, at which time the spreader 4^c engages stop 1^b and is swung thereby to the position shown in Fig. 3, allowing spring 4^b 15 to close the grippers upon the bobbin as indicated; while springs 8 will have swung levers 6 so that the strippers 6^b engage the quill as shown in Fig. 3. The cross head may have its openings engaging guides 5 20 slightly rounded, as indicated at 3^c, and may be provided with lubricating cups, indicated at 3^d.

Operation.

25 The hopper is so designed that the quills will descend one at a time to the opening in the bottom thereof into the position indicated in Fig. 2. As the grippers 4 move toward the hopper they remain open until they 30 are in position to engage the head of a quill exposed in the recess in the lower part of the hopper just before which the spreader 4^c engages stop 1^b, and as the cross head continues to move toward the hopper the spring 35 4^b closes the grippers upon the head of the bobbin; previous to which the springs 8 cause the strippers 6^b to engage the quill as indicated in Fig. 3.

Then when the cross head moves rearward 40 the grippers pull the bobbin from the hopper and between the strippers which clean it of all ravelings, etc., and when the cross head nears its rearmost position, as shown in Fig. 2, the spreader 4^c engages the stop 1^e 45 and spreads the grippers apart, releasing the spindle 10 as indicated in Fig. 2, and at about the same time the cross head engages the stops 5^c and pulls the guides 5 slightly backward, causing the levers 6 to swing and 50 separate the strippers 6^b, which permits the lowermost quill in the hopper to drop into position for removal. When the cross head starts forward again the springs 8 close the strippers upon the bobbin, as indicated in Fig. 3, and when the grippers have nearly 55 reached the bobbin engaging position the spreader 4^c is thrown backward as indicated in Fig. 3, and the grippers engage the bobbin as before described.

60 It will be seen that the machine when properly constructed will be entirely automatic in operation, and that if the bobbins are properly placed in the hopper they will be successively withdrawn therefrom and 65 cleaned.

Having thus described my invention, what I claim as new and desire to secure by Letters Patent is:

1. A machine for automatically cleaning quills for cotton weaving machines, comprising a hopper having a recess for exposing the heads of the quills, means for withdrawing the quills from said hopper, and spring controlled cleaning plates for stripping the fuzz from the quills as they are withdrawn from the hopper. 70

2. In a machine of the character described the combination of a recessed hopper, pivoted arms, cleaner plates carried by said arms, spring jaw members for withdrawing 80 the quills from the hopper, and means for actuating the jaw members and the cleaning plates.

3. In a bobbin stripping machine comprising yieldable stripping jaws, gripping jaws adapted to engage the base of the bobbin and draw the barrel thereof through said stripping jaws, and means for opening said gripping jaws to discharge the stripped 85 bobbins. 90

4. In a machine of the character specified, the combination of a frame, spring actuated levers pivoted on such frame, strippers attached to said levers, a reciprocating member, grippers attached to said member adapted to engage a quill, means for causing the grippers to engage a quill at the proper time, and means for causing the grippers to release the quill at the proper time. 95

5. In a machine of the character specified, the combination of a frame, spring actuated levers pivoted on such frame, strippers attached to said levers, a reciprocating cross head, grippers attached to said cross head adapted to engage a quill, means for reciprocating said cross head, guides for said cross head, and means operated by the cross head, and guides for causing the strippers to engage or disengage a quill. 100

6. In a machine of the character specified, the combination of a frame, a quill feeding hopper, spring actuated strippers, a reciprocating member, gripper bars attached to said member adapted to engage a quill, means for reciprocating said member, guides for said cross head, and means whereby the cross head controls the strippers, and means for causing the grippers to engage and release a quill at the proper times. 115

7. In a machine of the character specified, the combination of a frame, a quill feeding hopper, spring actuated levers pivoted on such frame, strippers attached to said levers, a reciprocating member, gripper bars attached to said member adapted to engage a quill, means for reciprocating said member, guides for said cross head, means whereby the cross head causes the strippers to separate when a quill has been withdrawn from the hopper, and means for causing the gripp- 120 125 130

pers to engage a quill at the proper time, and means for causing the grippers to discharge the quill at the proper time.

8. A machine of the character described 5 comprising a frame, a crank shaft journaled thereon, spring jaw members connected to said shaft adapted to engage the base of a bobbin and draw the barrel thereof through the stripping plates, means for opening and 10 closing said jaw members, and stripping plates for cleaning the quills.

9. A quill cleaning machine comprising a 15 crank shaft, spring jaw members connected to said crank shaft adapted to engage the base of a bobbin and draw the barrel thereof through the stripping plates, means for holding said members normally separated, means for closing said jaws to engage a quill, and stripping plates for cleaning the threads 20 from the quills.

10. A machine for automatically cleaning bobbins comprising a hopper, means for engaging the heads of the bobbins and withdrawing them from said hopper and through 25 the stripping means, and means for stripping the bobbins.

11. In a machine of the character described 30 comprising the combination of a hopper, strippers beside the hopper, grippers for with- drawing bobbins from the hopper and through the stripping means, means for actuating the grippers, and means for operating the strippers.

12. A machine of the character described 35 comprising a frame, a shaft journaled thereon, spring actuated bobbin grippers adapted to engage the heads of the bobbins and draw them through the strippers, connections for reciprocating the grippers from said shaft, 40 means for opening said grippers preparatory to receiving a bobbin, means for closing the grippers, and strippers for cleaning the bobbins.

13. A bobbin cleaning machine comprising 45 a crank shaft, grippers actuated by said crank shaft adapted to engage the heads of the bobbins and draw them through the strippers, means for opening said grippers preparatory to receiving a bobbin, means for closing said grippers to engage a bobbin, and strippers for removing waste, etc., from the bobbins.

14. A bobbin stripping machine comprising 50 strippers, grippers adapted to engage the head of a bobbin and draw the barrel thereof through said strippers, and means for positively opening said grippers to release the stripped bobbin.

15. In a machine of the character specified 55 the combination of reciprocatory grippers adapted to engage the head of a bobbin, strippers adapted to engage the body of the bobbin, means for causing the grippers to engage the head of a bobbin and draw 60 the body thereof between the strippers, and

means for positively opening the grippers to release the cleaned bobbin.

16. In a machine of the class described, 70 stripping mechanism adapted to engage the barrel of a bobbin, gripping mechanism and means for causing the same to engage the base of the bobbin and draw the barrel thereof through said stripping mechanism, and means for actuating said gripping mechanism to release the stripped bobbin. 75

17. In a machine of the class described 80 stripping mechanism comprising yieldable jaws adapted to engage the barrel of a bobbin, gripping mechanism, and means for causing the same to engage the base of the bobbin and draw the barrel thereof through said stripping jaws and means for actuating said gripping mechanism to release the stripped bobbin.

18. In a bobbin stripping machine, 85 yieldable stripping jaws adapted to engage the barrel of a bobbin, means for separating said stripping jaws for the reception of the bobbin, a reciprocating gripper having yieldable jaws adapted to engage the base 90 of the bobbin and draw the barrel thereof through said stripping jaws, and means for separating said gripping jaws to release the stripped bobbin.

19. A machine of the character described 95 comprising a frame, a crank shaft journaled thereon, spring jaw members connected to said shaft, means for positively opening said jaw members preparatory to receiving a bobbin and means for closing said jaw members, 100 and stripping plates for cleaning the bobbin.

20. In a bobbin stripping machine comprising yieldable stripping jaws, gripping jaws adapted to engage the base of the bobbin and draw the barrel thereof through said stripping jaws, means for opening said gripping jaws to discharge the stripped bobbin; and means for feeding the bobbins to the gripping jaws. 105

21. In a machine of the class described the 110 combination of a feed hopper; with stripping mechanism adapted to engage the barrel of a bobbin, gripping mechanism and means for causing the same to engage the base of a bobbin and draw it from the hopper and through said stripping mechanism, and means for actuating said gripping mechanism to release the stripped bobbin. 115

22. In a machine of the class described the 120 combination of a feed hopper; with stripping mechanism comprising yieldable jaws adapted to engage the barrel of a bobbin, gripping mechanism, and means for causing the same to engage the base of the bobbin and withdraw it from the hopper and draw the barrel thereof through said stripping jaws and means for actuating said gripping mechanism to release the stripped bobbin. 125

23. In a bobbin stripping machine the 130

combination of a feed hopper; with yieldable stripping jaws, gripping jaws adapted to engage the base of the bobbin and withdraw it from the hopper and draw the barrel thereof through said stripping jaws, and means for opening said gripping jaws to discharge the stripped bobbin.

24. In a bobbin stripping machine the combination of a feed hopper; with yieldable stripping jaws adapted to engage the barrel of a bobbin, means for separating said stripping jaws for the reception of the bobbin, a reciprocating gripper having yieldable jaws adapted to engage the base of the bobbin and withdraw it from the hopper and draw the barrel thereof through said stripping jaws, and means for separating said gripping jaws to release the stripped bobbin.

25. In a bobbin stripping machine, yieldable stripping jaws adapted to engage the barrel of a bobbin, means for separating said stripping jaws preparatory to the reception of the bobbin, a guide for said bobbin, a reciprocating gripper adapted to engage the base of the bobbin and draw the barrel thereof through said stripping jaws and means for releasing the stripped bobbin from said gripping jaws.

26. A bobbin stripper comprising stripping members, a gripper having spring jaws adapted to engage the base of the bobbin and draw the barrel thereof through said stripping means, a crank shaft connected to said

gripper and a hopper for automatically feeding bobbins to the said gripper, from which hopper the bobbins are drawn in the stripping operation. 35

27. A bobbin stripper comprising stripping members, a reciprocating cross head having grippers adapted to engage the base of the bobbin and draw the barrel thereof through said stripping members, means for reciprocating said cross head, a crank shaft and a pitman connecting said lever and cross head, and a hopper for automatically feeding bobbins to the said gripper from which hopper the bobbins are drawn in the stripping operation. 40

28. A bobbin stripper comprising a table, stripping members having bobbin engaging means and a relatively movable coöperating gripper adapted to draw a bobbin through said stripping members to remove the waste therefrom mounted on said table, and means 45 for actuating said stripping members and said gripper; with a feed hopper for automatically directing bobbins head first into position to be seized by the gripper, from which hopper the bobbins are drawn in the stripping operation. 50

In testimony that I claim the foregoing as my own, I affix my signature in presence of two witnesses.

GEORGE W. UTSMAN.
